UNITED STATES PATENT OFFICE.

ZACHRIAH TISHER AND CHARLES T. LITCHFIELD, OF SPOKANE, WASHINGTON.

FLANGE-OILER.

1,121,055.

Specification of Letters Patent. Patented Dec. 15, 1914.

Application filed September 18, 1913. Serial No. 790,474.

To all whom it may concern:

Be it known that we, ZACHRIAH TISHER and CHARLES T. LITCHFIELD, citizens of the United States, residing at Spokane, in the county of Spokane and State of Washington, have invented a new and useful Improvement in Flange-Oilers, of which the following is a specification.

This invention relates to improvements in wheel flange oilers or lubricators of that class wherein a pressure fluid is employed for feeding the lubricant.

It is one of the objects of this invention to eliminate waste of the lubricant by returning the same to the source of supply after the feed of lubricant has been shut off so as to avoid the loss of lubricant which has been released from the shut-off, and which has not yet reached the wheel flange.

A further object is to provide an improved form of oil applying wheel, adapted for engagement with the wheel flange, by reducing the surface of the oil applying wheel to approximately the area of its contact with the wheel flange, so as to avoid the delivery of lubricant to portions of the oil applying wheel, which does not engage the wheel flange.

A further object is to provide an oil feeding structure wherein the same may either be advanced into operative engagement with the wheel flange by pressure of air and oil, or wherein advancing movement toward an operative position is effected by air or fluid pressure alone.

A further object is to provide a feed reservoir connected with the supply reservoir, so as to maintain a supply or level of oil in the latter for feeding action by the pressure fluid, the feed reservoir being merely under atmospheric pressure and not being subject to any pressure from the supply cylinder.

A further object is to provide an improved form of feeder for the oil applying means, whereby the oil fed will be localized when discharged on that portion of the oil applying wheel, which comes in contact with the wheel flange.

Other objects and features of the invention will be more fully described in connection with the accompanying drawings, and will be more particularly pointed out in and by the appended claims.

In the drawings:—Figure 1 is a view partly in section and partly in elevation of

a railway vehicle, showing the application thereto of one form of our invention. Fig. 2 is a plan view thereof with parts broken away. Fig. 3 is a view similar to Fig. 1 illustrative of a modified form of our invention. Fig. 4 is a plan view of the device shown in Fig. 3, detached from the vehicle. Fig. 5 is a side elevation of the structure shown in Fig. 4. Fig. 6 is a front elevation thereof. Fig. 7 is a sectional view on line 7—7 of Fig. 4. Fig. 8 is a sectional view on line 8—8 of Fig. 4. Fig. 9 is a sectional view on line 9—9 of Fig. 8. Fig. 10 is a sectional view of an oil supply valve controlling plunger, detached from its associate parts. Fig. 11 is a sectional view of an oil supply conduit valve spindle, detached from its associate parts. Fig. 12 is a sectional view of an air controlling valve, showing the same in one position of adjustment. Fig. 13 is a similar view, showing the valve in another position of adjustment.

Like characters of reference designate similar parts throughout the different figures of the drawings.

As illustrated, 1 designates the body of a railway vehicle and 2 the truck thereof, the latter being illustrated in supported relation with one of the truck flanged wheels 3. An air supply tank 4 is indicated in a position below the car body and is provided with a supply pipe 5, which delivers to an air controlling valve 6. The air controlling valve 6 is connected with a pipe 7, which exhausts to atmosphere and is also connected with a supply pipe or oil feed or supply reservoir 8. A controlling handle 9 is provided for operation of a valve closure 10. The valve 6 is a three-way valve and when the closure 10 is in the position shown in Fig. 12, exhaust is effected from the supply reservoir 8 direct to atmosphere through pipe 7, as indicated by the arrows. When the valve is in the position shown in Fig. 13, communication is established between supply pipe 5 and supply reservoir 8 and exhaust through 7 is cut off.

The supply reservoir 8 depends from its connection with valve 6, and near its lower end said supply reservoir 8 is connected by a pipe 11 with a feed reservoir 12. The pipe 11 is provided with a check valve 13, which is arranged to shut off return from the reservoir 8 to the reservoir 12, but which permits of a gravity flow from reservoir 12 to reservoir 8. Thus when the oil in supply

reservoir 8 is not under pressure, the level of its contents will be fed to a level equaling that of the feed reservoir 12, so that a supply will always be afforded in the reservoir 8. A valve 14 is preferably disposed in reservoir 12 and forms the inlet to pipe 11 and is provided with a controlling stem and handle 15. By means of the valve 14, the supply or feed may at any time be cut off to reservoir 8.

In the preferred embodiment of our invention, oil under air pressure is utilized to advance the oil supply device for applying oil to the flange wheel into an operative position. In an alternative embodiment of our invention, air alone is utilized to advance said device into an operative position and the oil is supplied under air pressure.

Referring to Figs. 7, 8 and 9, 16 designates a bracket or support, which is adapted to be fixed to the truck 2. A valve or plunger 17 is fixed in bracket 16 and is provided with an annularly grooved nipple 18 to which a flexible connection 19 is attached, said connection 19 being secured to a pipe 20 communicating with the supply pipe or reservoir 8. The plunger 17 is provided with a bore 21 extending throughout its length to its discharge end 22. The plunger 17 is provided with a plurality of annular grooves 23 to provide oil receiving cavities to lubricate the periphery of the plunger. In two of the end grooves 24 we may provide suitable packing to prevent bypass of oil.

A cylinder 25 is slidably mounted upon the plunger 17, and is provided with a head 26 against which oil and air, or more properly speaking the oil under air pressure engages to advance the cylinder 25 to an operative or oil applying position. A suitable packing 27 may serve as an abutment to neutralize shock resulting from return impact of the cylinder head with the end of the plunger. Return movement of the cylinder is effected by means which may comprise springs 28, adapted for connection with the cylinder head at 29, and with the bracket 16 at 30.

Advancing movement of the cylinder 25 under oil pressure through the bore 21 will open a port 31 to admission of oil supply in the cylinder between the head 26 and the end of the plunger 22. Port 31 delivers to a milled off or recessed portion 32 of a valve conduit spindle 33, which is disposed at right angles to the plunger 17. The spindle 33 is provided with a port 34, which leads from the milled off recess 32 to a bore or conduit 35, having feed member discharge ports 36 and 37. The end of the bore 35 may be closed by any suitable form of plug 38. The spindle 33 is mounted in the cylinder structure 25 and stuffing boxes or packing glands 39 serve to prevent egress

of oil lengthwise and exteriorly of the spindle 33 and also to permit of longitudinal movement of said spindle. One end of the spindle 33 is reduced to form a shoulder 40, and on the reduced end of said spindle we mount oil feeders 41 and 42. Said feeders are jammed against shoulder 40 by a nut 43, so as to be nonrotatively secured to the spindle 33. The spacing element 44 is interposed between said feeders to hold the same in proper spaced relation. Feeder 41 is provided with a port 45, which registers with the elongated discharge port 36, and likewise, feeder 42 is provided with a port 46, which registers with elongated discharge port 37. The ports 36 and 37 are sufficiently long to afford registry with the ports 45 and 46 irrespective of relatively limited adjustments to take up wear.

Means is provided for preventing rotation of the feeders 41 and 42 and the spindle 33 and permitting longitudinal shifting movement thereof. As shown, such means may comprise a lug 47, adapted to engage a slot 48 formed in an arm 49 anchored to the cylinder structure 25.

Oil supplying disks or wheels 50 and 51 engage the feeders 41 and 42 in a manner to receive the oil discharged from ports 45 and 46, and as shown, said wheels 50 and 51 have an overlapping outside engagement with said feeders. Disk 50 is recessed at 52 so as to localize its oil supplying areas to outer peripheral portions thereof, as indicated at 54. By reason of this construction, we prevent oil from spreading, under feed supply, throughout the facial area of each disk and thereby effect a very material economy.

The oil applying disks 50 and 51 are shown threaded upon a sleeve 56, which is slidable upon a stud 57, mounted in the cylinder structure 25. When the disks are in place, they are locked by jam nuts 58 and 59. Springs 60 and 61 yieldingly resist movement of the sleeve 56 in opposite directions from the position shown, and spring 60 abuts against structure 25 while spring 61 abuts against a suitable washer 62.

The disks 50 and 51 are suitably flared so as to insure engagement with the flange of wheel 3 and in view of the fact that the bracket 16 is mounted on the truck 2, it will be seen that said disks will always be in approximately alined relation with the wheel flange. However, any slight lack of registry will be accommodated by the sliding movement afforded the sleeve 56 and the flared disks will serve to grasp opposite faces of the wheel flange and position themselves in accordance with any lateral play movement of the truck wheel with respect to the truck both on straight and curved lines of track. As the oil applying disks are shifted by relative play of the truck

wheel, they will likewise shift the feeders 41 and 42 and the spindle 33, and the latter will always be in communication with port 31 by reason of the elongated recess 32, so that in all positions which the spindle 33 may assume a supply of oil will be effected.

The port 31 is L-shaped and at its lower portion we provide means for controlling the flow of oil, which may be in the form of 10 a needle valve 63 which enters the port from a lateral position, as clearly shown in Fig. 9.

It will now readily be seen that when air pressure is shut off through valve 6, the springs 28 will instantly return the cylinder 15 structure 25 to the position shown in Fig. 8, thereby cutting off port 31 and causing return of the major portion of the oil supply, back to the supply reservoir 8, thereby avoiding waste. Such quantity of oil as may be 20 retained in the spindle 33 will be negligible and will not flow out of the spindle by reason of the lack of an air vent. Immediately upon release of pressure of air on the column of oil in reservoir 8, the check valve 25 13 will instantly open under the head of oil in reservoir 12 so as to replenish reservoir 8.

In the form of the invention just described, we provide a guide 64, which is mounted in bracket 16 and which projects 30 into cylinder structure 25 at 65, so as to prevent rotation of the cylinder structure on plunger 17. However, when it is desired to advance the disks 50 and 51 by air pressure instead of under the oil fed pressure, we may 35 provide the guide 64 with a bore 66 opening to the cylinder head 26, a suitable packing 67 being interposed for a purpose similar to packing 27. The guide 64 is provided with a nipple 68, adapted for attachment 40 to a flexible connection 69 communicating with a pipe 70. Pipe 70 is directly connected with valve 6 so that air under pressure will force the cylinder structure forwardly. Supply reservoir 8 will be connected to pipe 70 so that sufficient air pressure will be available to impart a force feed 45 to the oil simultaneously with pressure advancement of the cylinder structure.

While we have described the form shown 50 in Fig. 8 as a modification of the preferred form, still, it will be seen that where it is desired to merely utilize the valve-like plunger 17 for oil feed under pressure to 55 advance the device to an oil applying position, the plunger 64 may simply serve as a guide and, therefore, it will be seen that we have embodied in this one structure two forms of our invention, and in either utility 60 all of the parts will coact and function and no part will remain idle, although in the first-named form the plunger 64 will not function in its most complete capacity.

It is believed that the advantages and 65 utility of our invention will be fully understood from the foregoing description, and

while we have herein shown and described specific forms of our invention, we do not wish to be limited thereto except for such limitations as the claims may import.

We claim:—

1. In a wheel flange oiler, a pair of oil applying disks spaced apart from each other and having adjacent faces for engagement with opposite sides of a wheel flange, and oil feeders projecting between said disks and 70 having ports discharging on the adjacent faces of said disks, substantially as described.

2. In a wheel flange oiler, a pair of oil applying disks spaced apart from each other 80 and having adjacent faces for engagement with opposite sides of a wheel flange, means slidably supporting said disks for movement with the wheel flange, oil feeders projecting between said disks and having ports 85 discharging on the adjacent faces of said disks, and means slidably supporting said feeders for lateral movement with said disks, substantially as described.

3. In a wheel flange oiler, a pair of oil applying disks spaced apart from each other and having adjacent faces for engagement with opposite sides of a wheel flange, oil feeders projecting between and engaging the inner faces of said disks and having ports 95 discharging on said inner faces, and parallel supports for slidably mounting said disks and feeders, substantially as described.

4. In a wheel flange oiler, a pair of oil applying disks provided with adjacent convexly curved faces near the peripheries thereof, and concavely curved feeders engaging said faces and having ports for discharging oil thereon, substantially as described.

5. In a wheel flange oiler, a pair of oil applying disks for engagement with opposite faces of a wheel flange, a stud shaft rotatably and slidably supporting said disks, yielding means resisting movement of said 110 disks longitudinally of said stud shaft, feeders having ports discharging on said disks, an oil supplying spindle supporting said feeders and having ports discharging there- 115 to, means slidably supporting said spindle in parallel relation with said stud shaft, and means preventing rotation of said spindle and feeders, substantially as described.

6. In a wheel flange oiler, a device movable toward a wheel flange for applying oil thereto, a pair of plungers slidable with respect to said device and one of said plungers communicating with a source of supply of oil, and means for controlling a supply of air under pressure to the other plunger 125 to advance said device into an oil applying position with respect to said wheel flange, substantially as described.

7. In a wheel flange oiler, a device movable toward a wheel flange for applying oil 130

- thereto, a pair of plungers slidable with respect to said device and one of said plungers being connected with a source of supply of oil, and means controlling a supply of air under pressure for forcing oil through said oil plunger to said device and forcing air through the remaining plunger to advance said device into an oil applying position, substantially as described.
10. 8. In a wheel flange oiler, a device movable toward a wheel flange for applying oil thereto, a pair of plungers slidable with respect to said device, a connection for one of said plungers to a source of supply of oil, a connection for the other of said plungers to a supply of air under pressure to advance said device to an oil applying position, and means connecting said supply of air pressure with said first-named connection for utilizing said supply of air pressure to feed oil to said device through said first-named connection, substantially as described.
9. In a wheel flange oiler, a device movable toward a wheel flange for applying oil thereto, a valve plunger slidable in said device for conveying and controlling the supply of oil thereto, an oil supplying spindle slidable in said device and having an inlet connection for control by said valve plunger, and oil feeders mounted on and communicating with said spindle, substantially as described.
10. In a wheel flange oiler, an oil applying disk having an annular oil applying portion and being recessed with respect to said portion to cause the latter to project from the remainder of the disk, and means engaging and applying oil onto said portion, substantially as described.
40. 11. In a wheel flange oiler, an oil applying disk having an annular oil applying portion on one side face thereof and being recessed with respect to said portion to cause the latter to project laterally from said side face of said disk, and means engaging and applying oil onto said portion, substantially as described.
12. In a wheel flange oiler, an oil applying disk provided with a curved oil applying portion, and a feeder engaging and applying oil on said portion and having a part thereof shaped to conform to the curvature of said portion, substantially as described.
13. In a wheel flange oiler, a wheel having a flange, a non-absorbent rotary oil applying member having an annular oil applying and receiving swath of reduced area with respect to the total annular area of said member and engaging said wheel flange to apply oil thereon, and a non-absorbent feeder engaging and directly applying oil to the annular swath of said member whereby only that portion of said member engaging said wheel flange will be supplied by said feeder, substantially as described.
14. In a wheel flange oiler, a wheel having a flange, a metal disk having a limited annular area in engagement with said flange to apply oil thereon, and a metal feeder having a discharge portion shaped to engage said limited annular area and having a port opening within said discharge portion for discharging oil onto said limited area, substantially as described.
15. In a wheel flange oiler, a ported oil supplying member, a spindle slidable in said member and having a conduit provided with an intake terminal for receiving oil from said member irrespective of the position of said spindle and said spindle having an outlet terminal, a feeder fixed on said spindle and having a port in registry with said outlet terminal, and an oil applying member receiving oil from said feeder, substantially as described.

In testimony whereof we hereto affix our signatures in the presence of two subscribing witnesses.
